ENGINE STARTING MECHANISM

Raymond P. Lansing, Montclair, N. J., assignor to
 Eclipse Machine Company, Elmira Heights,
 N. Y., a corporation of New York

Application August 8, 1929, Serial No. 384,444

8 Claims. (Cl. 123—179)

This invention relates to starting mechanism for internal combustion engines.

One of the objects of the invention is to provide novel engine starting apparatus adapted for 5 manual actuation which is small, light and compact and at the same time rugged and powerful in operation.

Another object is to provide a novel hand starting apparatus for internal combustion engines 10 which is adapted for cranking about angularly related axes and which embodies means for preventing reverse rotation of the cranking shaft to prevent injury to the operator in case of backfire. For claims to this feature, per se, reference is to 15 be had to my copending application Serial No. 427,935 filed February 12, 1930.

A further object is to provide novel hand starting apparatus embodying a manually operable cranking shaft which is drivably connected with 20 means for cranking an engine and with a booster magneto.

Another object is to provide novel hand starting apparatus embodying in a self-contained unit a manually operable means for cranking an engine 25 and driving a booster magneto, which unit is adapted for detachably mounting a booster magneto thereon in driving engagement with said driving means.

Another object is to provide a hand starting 30 mechanism embodying manually operable driving means and a novel driving coupling whereby a booster magneto may be drivably engaged with or disengaged from said driving means.

One embodiment of the invention has been 35 illustrated in the accompanying drawings, but it is to be expressly understood that said drawings are for purposes of illustration only and are not to be construed as a definition of the limits of the invention, reference being had to the appended 40 claims for this purpose.

In said drawings:

Fig. 1 is an elevation, partly in section, of one embodiment of the invention;

Fig. 2 is a detail view of one form of means 45 for shifting the driven member to engine cranking position; this particular form of shifting means being disclosed and claimed in my copending application No. 341,145, filed February 19, 1929.

Fig. 3 is a sectional view taken on the line 3—3 50 of Fig. 1;

Fig. 4 is a section taken on the line 4—4 of Fig. 1; and

Fig. 5 is a detail of a modification of the means 55 shown in Fig. 2 for shifting the clutch member to cranking position.

Referring now to the drawings, wherein like reference numerals indicate like parts throughout the several views, the starting mechanism is preferably housed in a sectional casing 6 which may be suitably secured as by means of bolts 7 to the 60 housing of an internal combustion engine to be started, a portion of said housing indicated at 8. A cranking shaft 9 is rotatably mounted in the housing 6 in suitable bearings which, as shown, comprise a bushing 10 and a ball bearing 11. The 65 opposite sides of the inner end of the cranking shaft are flattened and the flattened surfaces extend from the inner end of the cranking shaft through the ball bearing 11. A bevel gear 12, for a purpose hereinafter described, is mounted on the 70 cranking shaft on the outer side of the ball bearing 11 and has driving engagement with said shaft due to its flat surfaces. On the inner side of said ball bearing is a spacing washer 13 adjacent to which is mounted a relatively large gear 14 which 75 likewise has driving engagement with said cranking shaft and constitutes a portion of a train of reduction gearing for driving a booster magneto, as described more fully hereinafter. On the inner side of gear 14 is a spacing washer 15 and adjacent 80 thereto is a small pinion 16 having driving engagement with the cranking shaft, a nut 17 on the inner reduced end of said cranking shaft holding the above parts on the shaft in assembled relation.

The cranking shaft 9 is drivably connected, preferably through suitable reduction gearing, with a clutch jaw 18 that is adapted to engage a corresponding clutch jaw 19 formed on a member of an engine to be started. In the form shown, 90 said reduction gearing is of the planetary type and accordingly the gear 16 constitutes a sun gear which meshes with a plurality of planetary gears, preferably three in number, and each corresponding in form, function and construction to the one 95 shown in section at 20. Said planetary gears in turn mesh with a stationary internal ring gear 21 secured to the casing 6 in any suitable manner as by means of bolts or studs 22. A dowel pin 23 preferably extends into the casing 6 and ring gear 100 21 to take up thrust and prevent shearing of screws 22. Planetary gears 20 are rotatably mounted in any suitable manner on a rotating driving barrel which, as shown, is constituted by a cup-shaped member 24 that is surrounded by a 105 bearing sleeve 25 preferably having a pressed fit therewith and is secured to a base member 26 in any suitable manner as by riveting. Screws 27 are threaded into member 26 and are surrounded by sleeves 28 which are countersunk in said mem- 110

ber. A bushing 28^a surrounds sleeve 28 to form a suitable bearing for planetary gear 20. Screws 27 also hold a retaining ring 29 which maintains the planetary gears in operative position.

5 The rotation of the driving barrel is transmitted, preferably, through a suitable yielding driving connection to the clutch jaw 18 and means are provided for shifting said clutch jaw axially into engagement with the clutch jaw 19 when the driving barrel rotates. In the form shown, an interiorly threaded nut 30 is positioned within the driving barrel and is drivably connected thereto by means of a friction clutch comprising a plurality of friction disks 31. The cup-shaped member 24 is provided with slots 32 in which a plurality of the disks 31 are splined, the remaining disks being splined to the outer surface of the nut 30. The splines on the nut 30 are turned outwardly at the outer end of said nut to form lugs 33 against which is seated a spacing member 34. A spacing member 35 and a plate 36 rest against the innermost friction disk of the clutch, said plate being provided with tongues 37 which engage between the splines on the nut 30. The disks 31 are held in frictional engagement by means of a plurality of coil springs 38, the tension of which may be adjusted by means of a nut 39 threaded on the outer end of the nut 30. A ring 40 provided with studs 41 may be employed to maintain the coil springs 38 in spaced relation around the nut 30.

Suitable means are provided for transmitting the rotation of the nut 30 to the clutch jaw 18 and for shifting the latter axially into engagement with the clutch jaw 19. Accordingly a short threaded shaft 42 is positioned in the interiorly threaded nut 30, said shaft being provided on its outer end with a stop nut 43 and having its inner end splined to engage a splined hub 44 formed on the clutch jaw 18. The shaft 42 is hollow, and a rod 45 extends therethrough which is provided at its outer end with a head 46. The inner end of said rod extends through an opening formed in the center of the clutch jaw 18 and carries a nut 47, a coil spring 48 being interposed between the clutch jaw 18 and the shaft 42. The periphery of the clutch jaw is provided with one or more notches 49 (Fig. 2) in which engage lugs 50 formed on a two-part ring 51. A coil spring 52 surrounds the ring 51 and maintains the inner surface thereof in frictional engagement with a lip 53 formed on an oil sealing member 54 that is suitably secured to the housing. The frictional drag of the ring 51 tends to retard the clutch jaw 18 and the shaft 42 with respect to the nut 30 when the latter rotates and to cause relative rotation therebetween, and the threaded engagement between shaft 42 and nut 30 is such that the shaft then travels to the left, as seen in Fig. 1, until the stop nut 43 engages a suitable shoulder 55 formed interiorly of the nut 30, whereupon the shaft and nut rotate together. Movement of the shaft to the left compresses spring 48 which resiliently urges the clutch jaw 18 inwardly or to the left, as seen in Fig. 1, into engagement with the clutch jaw 19. When the engine starts under its own power, the clutch jaw 19 overruns the jaw 18 and the inclined faces of the jaw teeth are effective to cause the jaw 18 to be moved outwardly or to the right.

It is desirable to provide means whereby the cranking shaft 9 may be rotated from different directions, as from the end or side of the starting mechanism, and likewise to prevent reverse ro-

tation of the cranking shaft in order to eliminate injuries to the operator in case of backfire of the engine. In order to crank the starter from one end thereof, the cranking shaft 9 is extended outwardly of the housing and is provided on its outer end with a member 56 pinned to the shaft at 57 and adapted to receive a hand crank (not shown). In the illustrated embodiment of the invention, means are likewise provided for cranking the starter from one side thereof, said means comprising a cranking shaft 58 (Fig. 3) substantially at right angles to the cranking shaft 9 and mounted in suitable bushings in the housing 6, said shaft having on its inner end a bevel gear 59 held thereon by a nut 60 and meshing with the bevel gear 12 on the cranking shaft 9. The outer end of the shaft 58 may be provided with a suitable member to receive a cranking handle, such as member 56 on cranking shaft 9, or when not in use may be provided with a nut 61 pinned thereto at 62. In order to prevent injuries from backfire, means may be employed to prevent reverse rotation of either of the cranking shafts, said means preferably comprising suitable ratchet mechanism mounted on either or both of said shafts. In the form shown, an exteriorly splined hub 63 is keyed to the cranking shaft 9 at 64 and is held longitudinally thereof by means of a spacing sleeve 65. A ratchet member 66 is splined to the hub 63 and is resiliently urged into engagement with a cooperating ratchet 67 mounted on the housing 6, a coil spring 68 being interposed between the ratchet member 66 and a spring plate 69 that is secured to the hub 63 for this purpose. The ratchet members permit free rotation of either or both cranking shafts in one direction to crank the engine, but in case of backfire, both shafts are prevented from rotating in the reverse direction.

In some instances it is desirable to operate a booster magneto from the starter mechanism when the engine is being started, the booster magneto being rotated by the starter cranking shaft at high speed through suitable reduction gearing. A booster magneto 70 of any suitable type is shown mounted on a plate 71, preferably formed integrally with the housing 6 and held thereon by suitable means such as a strap 72 passing around the magneto casing and secured at both ends to the plate 71 by means of holders 73 extending through said plate and provided on their lower ends with nuts 74. The shaft 75 of the magneto carries a clutch member 76 that is keyed thereto at 77 and is held thereon by means of a nut 78 threaded on the end of the shaft. One or more teeth 79 formed on said clutch member are adapted to engage corresponding notches 80 formed in a clutch member 81 that is rotatably mounted in the casing 6. A short shaft 82 is rigidly secured to the clutch member 81, preferably extending through and being riveted at 83 to said member. The end 84 of said shaft is seated in a suitable bearing recess formed in the casing 6 and teeth 85 formed on the shaft mesh with the teeth of gear 14. The pinion 85 and the gear 14 constitute reduction gearing driven by the cranking shaft 9 of the starter and housed within the starter casing, to which the shaft 75 of the booster magneto that is detachably mounted on the exterior of said casing may be drivably connected by means of the clutch members 76 and 81.

Fig. 5 illustrates a somewhat modified form of means for automatically shifting the clutch jaw 18 into engagement with the jaw 19 when the

starter is cranked. In this form, an oil sealing member is provided with a flange 86 constituting an annular friction surface around the clutch jaw 18. A cooperating friction surface is formed by a ring 87 which is mounted in spaced relation to the flange 86 by means of a pair of spacing rings 88 and 90, the latter having an outside diameter slightly less than the inside diameter of the ring 88. Ring 90 is frictionally engaged between the friction surfaces 86 and 87, said ring being provided with a lug which engages a notch 91 formed in the periphery of the clutch jaw 18. The operation of this modification is the same as that of the ring 51, lugs 50 and notches 49 shown in Fig. 2.

The operation of the apparatus is as follows: When it is desired to crank an engine, a cranking handle is fitted to the end of the cranking shaft 9, or to cranking shaft 58, and is rotated in the proper direction. The rotation of the cranking shaft 9 which is caused thereby is transmitted through the sun gear 16 and planetary gears 20 to the driving barrel. The interiorly threaded nut or sleeve 30 is likewise rotated through the friction clutch means 31, and owing to the frictional drag of the ring 51, as above described, the relative rotation between nut 30 and shaft 42 causes the latter to move to the left, compressing the spring 48 and yieldingly moving the clutch jaw 18 inwardly into engagement with the clutch jaw 19. In case the engine backfires, the cranking shaft 9 is prevented from rotating in the reverse direction by the ratchet members 66 and 67, and slippage between the friction disks 31 prevents breaking of any of the starter parts. As soon as the engine starts under its own power, the jaw 19, overrunning the jaw 18, forces the latter back to the position shown in the drawings.

When the booster magneto 70 is employed, the rotation of the cranking shaft 9 is transmitted through gears 14 and 85 to the magneto shaft, the latter rotating at relatively high speed to insure proper ignition when the engine is being started. It will be seen that the reduction gearing for operating the magneto is entirely enclosed within the starter housing and is drivably connected with the magneto shaft by a clutch which extends through the housing. Therefore when the magneto is unnecessary it may be detached by loosening the strap 72 and disengaging the clutch members 76 and 81, whereupon the entire magneto may be removed. The starter mechanism, however, remains a complete self-contained unit, the operation of which is in no way affected by the removal or attachment of the booster magneto thereto.

It will be obvious that the invention is not limited to the form shown in the drawings but is capable of a variety of embodiments. For example, any suitable type of magneto may be employed and other forms of clutch mechanism may be substituted for the driving coupling which connects the magneto shaft with the reduction gearing. The reduction gearing which drivably connects the clutch jaw with the crank and the magneto with the cranking shaft may also be substituted by gear trains of other designs and proportions. Likewise either the cranking shaft 58 or the outwardly extending portion of cranking shaft 9 may be omitted where the use to which the starter is to be put requires only one of them, and if such is the case the ratchet mechanism may be mounted on either shaft employed. Various other changes may be made in the form, details of construction, and arrangement of the parts without

departing from the spirit of the invention, and reference is therefore to be had to the appended claims for a definition of the limits of the invention.

What is claimed is:

1. Apparatus of the class described comprising in combination a housing having an opening therein and a mounting flange thereon, a cranking shaft rotatably mounted in said housing, a clutch member mounted in said housing and adapted to engage and crank a member of an engine to be started, means drivably connecting said clutch member and cranking shaft, a clutch member rotatably mounted in said opening and constituting a closure therefor, means drivably connecting said last named clutch member and said cranking shaft, a booster magneto mounted on said flange, and a clutch member drivably connected with said magneto and engaging said second named clutch member, said cranking shaft and clutch member being rotatable about axes disposed in a common plane perpendicular to the plane of said mounting flange. 90

2. Apparatus of the class described comprising in combination a housing having an opening 100 therein and a mounting flange thereon, a cranking shaft rotatably mounted in said housing, a clutch jaw mounted in said housing and adapted to engage and crank a member of an engine to be started, means drivably connecting said clutch 105 jaw and cranking shaft, a cup rotatably mounted in said opening and having a notched rim projecting exteriorly of said housing, said cup constituting a closure for said opening, means drivably connecting said cup with said cranking shaft, 110 a booster magneto mounted on said flange, a shaft for said magneto, and means on said shaft engaging the notches in the rim of said cup, said cranking shaft and clutch member being rotatable about axes disposed in a common plane perpendicular to the plane of said mounting flange. 115

3. In combination with a housing having a driving shaft extending therefrom, said housing having an outer surface disposed in a plane parallel to the axis of rotation of said driving shaft, a magneto having a current generating element rotatable about an axis parallel to said plane, means for drivably connecting said driving shaft and current generating element, and a housing for said magneto, said magneto housing being slidable along said plane surface for the purpose of adjusting said driving connection. 125

4. In combination with a housing having a driving shaft extending therefrom, said housing having an outer surface disposed in a plane parallel to the axis of rotation of said driving shaft, a magneto having a current generating element rotatable about an axis parallel to said plane, means for drivably connecting said driving shaft and current generating element, a housing for said magneto, said magneto housing being slidable along said plane surface for the purpose of adjusting said driving connection, and means extending through said plane surfaced portion of said housing for holding said magneto in adjusted position. 135

5. In combination with a housing having a driving shaft extending therefrom, said housing having an outer surface disposed in a plane parallel to the axis of rotation of said driving shaft, a magneto having a current generating element rotatable about an axis parallel to said plane, both said axes of rotation being disposed 145

- in a plane perpendicular to said first named plane, means for drivably connecting said driving shaft and current generating element, and a housing for said magneto, said magneto housing being slideable along said plane surface for the purpose of adjusting said driving connection. 80
6. In combination with a housing having a driving shaft extending therefrom, said housing having an outer surface disposed in a plane parallel to the axis of rotation of said driving shaft, a magneto having a current generating element rotatable about an axis parallel to said plane, both said axes of rotation being disposed in a plane perpendicular to said first named plane, means for drivably connecting said driving shaft and current generating element, a housing for said magneto, said magneto housing being slideable along said plane surface for the purpose of adjusting said driving connection, and means 85
- 10 extending through said plane surfaced portion of said housing for holding said magneto in adjusted position. 90
- 15 7. In combination with a housing having a driving shaft extending therefrom, said housing having an outer surface disposed in a plane 95
- 20
- 25
- parallel to the axis of rotation of said driving shaft, a magneto having a current generating element rotatable about an axis parallel to said plane, and means including a toothed clutch element constituting a part of the closure means for said first named housing, and engageable with a corresponding clutch element adjustably mounted on said current generating element for drivably connecting said shaft and current generating element. 80
8. In combination with a housing having a driving shaft extending therefrom, said housing having an outer surface disposed in a plane parallel to the axis of rotation of said driving shaft, a magneto having a current generating shaft rotatable about an axis parallel to said plane, means including a toothed clutch element constituting a part of the closure means for said first named housing, and engageable with a corresponding clutch element on said magneto shaft 95
- for drivably connecting said shafts, and means extending through said plane surfaced portion of said housing for holding said magneto in position to maintain said clutch elements engaged. 100
